CONTAINER END AND PROCESS FOR
MAKING SAME

Chester B. Thayer, Benton Harbor, Mich.

Application November 15, 1933, Serial No. 698,061

2 Claims. (Cl. 144—309)

The present invention relates to containers as baskets and the like; and its object is to provide improved ends for such containers, and an improved method of making such ends. Said 5 ends—the bottoms or top covers for the baskets and the like—comprise a peripheral or circuitous element or rim of wood or the like and a thin sheet element of wood or other suitable material fastened sidewise to the flat edge of the peripheral element.

My improved container end and improved method of making the same are particularly described in the body of this specification and illustrated by the accompanying drawing, in which:

15 Figure 1 is a top plan or face view of an anvil block having a circular groove receiving the peripheral element of a basket bottom with the sheet element of said bottom positioned thereon and shown partially broken away;

20 Figure 2 is a sectional view thereof taken on line 2—2 of Figure 1;

Figure 3 is an enlarged sectional view of a portion of the same taken on the same line;

25 Figure 4 is a top plan view similar to Figure 1 but showing a differently shaped groove in the block and illustrating the manner in which a bendable strip for forming the peripheral element may be inserted into said groove;

30 Figure 5 is a sectional view of a portion thereof taken on line 5—5 of Figure 4;

Figure 6 is an elevational side view of a portion of a basket of which said bottom forms a part;

Figure 7 is a view of said bendable strip; and

35 Figure 8 is a vertical sectional view of an obvious modified construction of the device in which the groove is formed by a vertical edge 22 and the pins 23.

As indicated in these views, I make or provide a block or anvil 1 with a circuitous groove 4 in its flat face 2 corresponding in shape and dimensions with the basket bottom designated generally 3 to be made. In Figure 1 this groove 4 is circular for the making of a circular basket bottom; but said groove may be of other shapes 40 to correspond with the bottoms of other desired shapes, as the groove of rectangular shape with rounded corners shown at 4¹ in Figure 4. The said peripheral element 5, circular for use in groove 4 or otherwise shaped as for use in groove 4¹, is inserted into the correspondingly shaped groove, the bottom flat side 6 of said element seating on the bottom 7 of the groove and the groove's sides 8 holding said element laterally.

55 Desirably however, I prepare an elongated

bendable strip 9 of suitable material as wood and bend and insert the same into the groove, the end 9¹ of the strip being first inserted as indicated in Figure 4, and then the rest of the strip is progressively inserted and finally the opposite end 10 of the strip, thus completing such insertion, the necessary bending and the inserting of the strip thus proceeding together.

As indicated, the opposite ends 9¹, 10 of the strip thus inserted are held in abutting relation in the groove. I then position a sheet 11, of suitable material as wood and desirably composed of plies 12, 13 arranged in crosswise relation and connected as by staples 14, on the outer edge 15 of the strip in the groove and fasten 15 said elements—sheet 11 and peripheral strip element 5—together as by nails or staples 16.

It will be seen that in a basket bottom or container end 3 thus made the extremities 17, 18 of strip 9 are securely held in endwise abutting relation so that there need be no overlapping connected ends of such a strip to form a bulge in the section of such a peripheral element where such an overlapping connection exists. The curved side of the container, as the staves 19 of 25 the basket 20, may be fastened to the bottom 3 as by nails or staples 21.

As indicated, the sheet element 11 may be of slightly greater diameter than the peripheral element 5, so that in making a downwardly tapering basket as that shown in Figure 6, the staves are inclined downwardly inwardly when nailed in place.

The anvil block, instead of having a groove as above described, may have an upwardly extending middle portion with a vertical edge 22 so that a shoulder 24 is formed as shown in Figure 8, the face of this middle portion being shaped correspondingly with the basket bottoms, etc. to be formed thereon. A strip 9 may be laid on the shoulder and held adjacent its end (as by a pin 23) against this vertical edge of said portion, and the strip progressively bent around said edge, and as such bending progresses the sheet 11 may be nailed to the strip's flat upper edge, this 40 process thus holding the strip in its bent form and securing the sheet in place thereon.

I claim:

1. A method of making a container end which comprises a curved peripheral element and a middle element fastened sidewise on the flat edge of the peripheral element, said method including the following acts: confining in fixed position one end of an elongated bendable strip, bending the strip progressively from said end to form the 55

peripheral element, holding the same in such bent position, positioning the middle element sidewise on the flat edge of the bent peripheral element, and fastening the mutually contacting surfaces of said elements together.

5 2. A method of making a container end which comprises a curved peripheral element and a thin middle element fastened sidewise on one flat edge of the peripheral element, said method including the following acts: inserting and hold-

ing one end of an elongated bendable strip in fixed position between spaced members of an anvil block, bending and guiding the strip progressively from said end to form the peripheral element, holding the same in such bent position with one of its flat edges resting on the block, positioning the middle element sidewise on the other flat edge of the bent peripheral element, and nailing said elements together.

CHESTER B. THAYER.
